(57) **CLAIM**

The ornamental design for a coffee press, as shown, and described.

DESCRIPTION

FIG. 1 is a perspective view of the coffee press;

FIG. 2 is a front view of the coffee press;

FIG. 3 is a rear view of the coffee press;

FIG. 4 is a left side view of the coffee press;

FIG. 5 is a right side view of the coffee press;

FIG. 6 is a top view of the coffee press; and,

FIG. 7 is a bottom view of the coffee press.

The broken lines illustrate a partially visible coffee plunger, which forms no part of the claimed design.
